UNITED STATES PATENT OFFICE.

NAPOLEON AUBUCHON, OF ST. LOUIS, MISSOURI, ASSIGNOR TO JOHN H. MUIR, OF ST. LOUIS, MISSOURI.

WINDOW-SCAFFOLD.

No. 869,127.

Specification of Letters Patent.

Patented Oct. 22, 1907.

Application filed October 27, 1906. Serial No. 340,910.

To all whom it may concern:

Be it known that I, NAPOLEON AUBUCHON, a citizen of the United States, residing at St. Louis, in the State of Missouri, have invented new and useful Improvements in Window-Scaffolds, of which the following is a specification.

This invention relates to an improved window bracket or scaffold, designed to provide a platform at the exterior of the window on which a person may stand 10 while painting, cleaning windows and performing like work.

The object of the invention is to provide a simple, inexpensive and efficient device of this character which is adapted to be folded in close compass for storage or transportation and to be adjusted to suit windows in which the sills vary in thickness or project to a greater or less extent beyond the wall, and which is braced to strengthen the parts thereof.

In the accompanying drawing,—Figure 1 is a side 20 elevation of a scaffold bracket embodying the invention. Fig. 2 is an outer end elevation thereof. Fig. 3 is a top plan view. Fig. 4 is a detail cross section on line 4—4 of Fig. 3. Fig. 5 is a view of a modified form of brace for the hinged legs.

25 The device comprises a frame embodying parallel side bars 1, upon the outer ends of which are laid and secured a series of cross slats forming a platform 2. The bars 1 carry parallel supporting bars 3 arranged upon the inner side thereof, said bars 3 being fitted to slide in 30 guides 4 fixed to the bars 1. Clamping devices are employed to secure the bars 3 in adjusted position, each consisting of upper and lower clamping members 5 and 6 engaging the upper and lower edges of the bars in rear of the guides 4, said members being connected 35 by a bolt 7 extending downward through recesses formed in the meeting faces of the bars. In this operation, the bolts permit a sliding adjustment of the bars 3 to the limit afforded by the length of the recesses in the meeting faces of the bars, which produce slots through 40 which the bolts project, as will be readily understood.

The upper end of the bolt is fitted with a thumb nut 8, by which the clamping members 5 and 6 may be loosened to permit adjustment of the supporting bars 3 and tightened to clamp said bars in adjusted position.

45 The inner or free ends of the bars 3 are provided with depending stops 9 adapted to bear against the inner side of the wall or sill of the window to hold the scaffold from outward movement. By the adjustable connection of the bars 3 with the bars 1 the scaffold is made 50 longitudinally extensible for application to window sills of different thicknesses or which extend to a greater or less extent beyond the surface of the wall.

The outer end of the scaffold is supported by inclined legs 10, having their lower ends beveled to abut against

the exterior wall of the building and hinged at their 55 upper ends to the outer ends of the bars 1, as indicated at 11, the upper ends of said legs being also beveled to bear against the undersides of the bars to reinforce and hold said legs against outward movement. The free end of each leg is connected with the adjacent bar 1 by 60 a pair of pivoted braces 12, the meeting ends of said braces being pivotally connected, as indicated at 13. The upper end of the upper brace and lower end of the lower brace are pivotally attached respectively to the bar 1 and leg 10 by bolts 14 and 15, such connection permitting the braces to be extended vertically in longitudinal alinement to reinforce and stay the bearing ends of the legs, as well as to permit said braces to swing outwardly on their pivotal connection 13 to adapt the 65 legs 10 to fold against the bars 1, thus adapting the device when the legs are swung inward and the bars slid outward in the guides 4 to be contracted, so that it may be packed or stored in close compass.

The legs 10 are connected at their lower ends by a cross piece 16 and above the same with cross braces 17. 75 U-shaped straps 18 are fastened to the outer ends of the bars 1 having their lower ends depending therefrom on opposite sides of the upper hinged end of each bracket to form a guide therefor. This guide adapts the legs to swing in a true plane and prevents lateral oscillation 80 thereof on the hinge 11, thus strengthening and reinforcing the hinged connection to a material extent.

In the use of the device, the bars 1 and 3 are extended across the window sill, the stops 9 arranged to bear against the inner face of the sill, the legs 10 unfolded and the scaffold adjusted as to length to suit the width of the sill by adjusting the bars 3 in the guides 4, thus bringing the lower ends of the legs 10 to bear against the outside of the wall of the building. The clamping screws 8 are then tightened to rigidly connect the parts of the scaffold, and the platform 2 will accordingly project to form an exterior support. 85

As shown in Fig. 5 the outer ends of the braces 12 may be formed with hooked portions 12' to engage the respective bolts 14 and 15, thus adapting said braces 95 to be detached when the scaffold is folded. Preferably the bars 1 are provided with a plurality of spaced openings 20 for the reception of the bolts 14, while the lower braces 12 and the legs 10 are similarly provided respectively with a plurality of openings 21 and 22 for the reception of the pivot bolt 15. This construction permits the braces to be adjusted for connection with the legs to adapt the latter to be swung outwardly to a greater extent when the scaffold is supported upon window sills jutting greater than a normal extent beyond the wall of the building. 100

The scaffold may be made of wood or metal, or the braces and fastening elements alone may be made of

metal and the remaining parts of wood, the construction in either case being simple enough to permit of the manufacture of the device at a low cost.

The adjustability of the structure adapts it to be 5 readily used as a window scaffold on buildings having sills varying greatly in width, thus increasing its range of usefulness and practical efficiency.

Having thus described the invention, what is claimed as new, is:—

- 10 The herein-described scaffold-bracket comprising a supporting frame consisting of parallel side bars having connecting members at their outer ends forming a platform, inwardly projecting guide loops upon said side bars, sliding supporting bars arranged on the inner sides of said side bars and engaging the guide loops, clamping members em- 15

bracing the bars in rear of the guides, bolts extending between the bars and connecting the clamping members and provided with nuts for adjusting said clamps to secure the supporting bars in adjusted position, stops carried by the inner ends of the supporting bars, legs hinged at their upper ends to the side bars at a point in rear of the outer ends of the latter, pairs of folding braces at opposite sides of the device pivotally connected to each other and to the side bars and to the legs, and guides secured to and depending from the outer ends of the side bars beyond the 20 hinges of the legs to engage and stay the hinged ends of the legs from lateral movement.

In testimony whereof, I affix my signature in presence of two witnesses.

NAPOLEON AUBUCHON.
